UNITED STATES PATENT OFFICE.

CHARLES M. McCORMICK, OF THE UNITED STATES NAVY.

NAVIGATING-PROTRACTOR.

SPECIFICATION forming part of Letters Patent No. 692,060, dated January 28, 1902.

Application filed October 21, 1901. Serial No. 79,390. (No model.)

To all whom it may concern:

Be it known that I, CHARLES M. McCORMICK, of the United States Navy, a citizen of the United States, have invented certain new and useful Improvements in Navigating-Protractors, of which the following is a specification, reference being had therein to the accompanying drawings.

This invention relates to a navigating-protractor and is particularly adapted for the solution of the three-point problem for the location of an object from the observation from three relatively-fixed points.

The invention has for an object to provide a skeleton protractor adapted to rest upon a chart or other surface and having its center within the rings free from all rules, hubs, or arms which obscure the chart or other surface upon which the operator is working.

A further object of the invention is to provide a structure consisting of three concentric rings, two of which have motions in azimuth with regard to the third, which is fixed and graduated, while each of the rings is provided with a diametrically-extended cord or wire, which by motion in azimuth can be placed in any designated angle to each other and have a point of common intersection at the center of the space within the rings.

Other and further objects and advantages of the invention will be hereinafter set forth, and the novel features thereof pointed out in the appended claims.

In the drawings, Figure 1 is a plan view of the protractor, and Fig. 2 a vertical section thereof. Fig. 3 is a detail vertical section through one of the securing-blocks for the movable rings. Fig. 4 is a similar view at a point where the base projects upward between the movable rings, and Fig. 5 is a detail section showing the manner of securing the wires or cords carried by the several rings.

Like letters of reference refer to like parts in the several figures of the drawings.

The letter A designates a base-plate forming a ring or annulus and having centrally thereon a raised portion A', bearing a series of graduations of any desired character—for instance, as shown in Fig. 1, where they extend for one hundred and eighty degrees to the right and left of a zero-point, thus forming

a completely-graduated circle. This graduated surface A' may be formed integral with the base A or secured thereto, and this base is provided with an indicating-strand—55 for instance, a cord or wire A²—extending across the diameter thereof from the zero-point to the one hundred and eightieth degree graduation. Mounted upon this base are two concentric rings movable in azimuth with relation to the portion A' and comprising an outer ring B and an inner ring C, each of which may be held in position by any desired means, although in Fig. 3 a securing-block D is shown, provided with tongues D' at opposite sides, 60 adapted to enter the peripheral grooves or ways B' and C' of the rings B and C, respectively, as shown in Figs. 3 and 4. This block is placed in a cut-away portion of the graduated ring A' and may be secured by a screw-fastening D². The outer ring B is provided with a diametrically-disposed cord or wire B² and an operating-knob B³, while the inner ring C is provided with a similar cord or wire C² and with an operating-knob C³. The base 70 A is also adapted to be held in position by means of a handle A³ on opposite sides suitably secured to the base.

In order to bring the diametric wires in as close proximity as possible at their point of 80 intersection so as to accurately determine the apex of an angle, the wire A² is mounted upon the upper surface of the base A and the wire C² upon the lower surface of the ring C, while the wire B² from the outer ring B is 85 carried over the graduated ring A' and inner ring C by means of a hanger B⁴, having its inner end B⁵ deflected downward to bring the wire into the proper plane.

Under some conditions it is desirable to 90 extend the line of the diametric wires, and this may be accomplished by various means. For instance, an extension-arm E may be provided and secured to the base A by means of an overlapping portion E', through 95 which the threaded handle A³ may pass. For this purpose an extension A⁴ is provided opposite the zero-point of the base, so that the edge E² of the arm will lie in line with the wire A², while any lateral movement of 100 this arm is prevented by the pins E³ entering suitable sockets in the extension A⁴. For

the purpose of extending the line of any of the other wires, an arm F is provided, having at its inner end a portion F³, formed upon the radius of the outer ring B, so that it can be placed and held in contact therewith while making any measurement.

The invention has been described as a "navigating-protractor," but it is adapted for use for numerous other purposes both in drafting and in mathematical calculations. When used for the purpose of locating the exact position of a vessel upon a chart, the rings are placed over the chart and the angles between three fixed objects are obtained by the use of a sextant in the usual manner. The rings are then moved to bring the right and left wires upon the lines of the angles indicated in order to disclose upon the chart the relative position of the ship to the fixed object observed. In this operation the entire instrument will be shifted upon the chart or map to bring the wires into alinement with the representation of the fixed objects there-to, so that the intersection of the wires at once indicates the position of the vessel and leaves unobscured all adjacent portions of the chart.

It will be obvious that changes may be made in the details of construction and configuration without departing from the spirit of the invention as defined by the appended claims.

Having described my invention and set forth its merits, what I claim, and desire to secure by Letters Patent, is—

- 35 1. A protractor comprising a stationary base-ring having an indicating-strand across its diameter, a plurality of relatively movable concentric rings, and an indicating-strand carried by and extending across the diameter of each of said movable rings and adapted to cross the strand of the base-ring at its mid-length; substantially as specified.
- 40 2. A protractor comprising a graduated base-ring, a movable concentric ring mounted thereon, and an indicating-strand carried by and extending diametrically across each ring in different horizontal planes to each other; substantially as specified.
- 45 3. A protractor comprising a graduated base-ring, movable concentric rings upon opposite sides of said base-ring, and indicating means extending diametrically across each ring; substantially as specified.
- 50 4. A protractor comprising a graduated base-ring, movable concentric rings upon opposite sides of said base-ring, indicating means extending diametrically across each ring, and a hanger for said indicating means

extending from the outer ring over the inner ring; substantially as specified.

5. A protractor comprising a graduated base-ring, movable concentric rings upon opposite sides of said base-ring, indicating means extending diametrically across each ring, and a securing-block having projections to engage each of said movable rings; substantially as specified.

6. A protractor comprising a plurality of relatively movable concentric rings, an indicating-strand extending diametrically across each of said rings, and an extension-arm removably secured to one of said rings; substantially as specified.

7. A protractor comprising a base having a graduated ring thereon, a movable concentric ring mounted upon said base, cords or wires extending diametrically of each ring, an extension from said base-plate, an extension-arm overlapping said extension, and a securing-handle passed through said arm and extension; substantially as specified.

8. In a protractor a base-plate having a centrally-disposed graduated ring thereon, an indicating-wire extending diametrically of said ring, concentric movable rings upon opposite sides of said graduated ring, diametric wires carried by each of said movable rings, and means carried by said graduated ring for holding the movable rings against vertical movement; substantially as specified.

9. In a protractor, a base-plate having a centrally-disposed graduated ring thereon, an indicating-wire extending diametrically of said ring, concentric movable rings upon opposite sides of said graduated ring, diametric wires carried by each of said movable rings, means carried by said graduated ring for holding the movable rings against vertical movement, and hangers carried by the outer movable ring and extending over the other rings to support the indicating-wire from said outer ring; substantially as specified.

10. A protractor comprising a plurality of relatively movable concentric rings, indicating means extending diametrically of each of said rings, and a separable extension-arm having a contact-face curved upon the radius of the outer face of said rings; substantially as specified.

In testimony whereof I affix my signature in presence of two witnesses.

CHARLES M. McCORMICK.
